(57) **CLAIM**

The ornamental design for a water bottle, as shown and described.

DESCRIPTION

FIG. 1 is a perspective view of a water bottle showing my new design;

FIG. 2 is a front view thereof;

FIG. 3 is a rear view thereof;

FIG. 4 is a right side view thereof;

FIG. 5 is a left side view thereof;

FIG. 6 is an enlarged top view thereof;

FIG. 7 is an enlarged bottom view thereof;

FIG. 8 is an exploded perspective view thereof;

FIG. 9 is an exploded front view thereof;

FIG. 10 is an exploded rear view thereof;

FIG. 11 is an exploded right side view thereof;

FIG. 12 is an exploded left side view thereof;

FIG. 13 is an enlarged exploded top view thereof; and,

FIG. 14 is an enlarged exploded bottom view thereof.

The broken line showing of the bottle bottom detail is for the purpose of illustrating portions of the water bottle and forms no part of the claimed design.

1 Claim, 14 Drawing Sheets
